UNITED STATES PATENT OFFICE.

CHARLES A. MYERS, OF NIAGARA FALLS, NEW YORK.

STREET OR STATION INDICATOR.

No. 845,886.

Specification of Letters Patent.

Patented March 5, 1907.

Application filed December 21, 1905. Serial No. 292,759.

To all whom it may concern:

Be it known that I, CHARLES A. MYERS, a citizen of the United States, residing at Niagara Falls, in the county of Niagara and State of New York, have invented certain new and useful Improvements in Street or Station Indicators; and I do declare the following to be a full, clear, and exact description of the invention, such as will enable others skilled in the art to which it appertains to make and use the same.

My invention relates to improvements in street or station indicators for electric cars, steam-cars, and the like.

The object of the invention is to provide a simple, durable, and efficient device of this character which may be mounted in cars of any description and which will be operated automatically to indicate to the passengers in said car each street or station as it is approached.

With the above and other objects in view the invention consists of certain novel features of construction, combination, and arrangement of parts hereinafter described and claimed.

In the accompanying drawings, Figure 1 is a front elevation, with the parts in section, of an indicating device constructed in accordance with my invention. Figs. 2 and 3 are similar views of the opposite ends of the device. Fig. 4 is a horizontal sectional view. Fig. 5 is a perspective view of portions of a trolley-pole and trolley-wire, showing my improved circuit-closing device, which is used in connection with the indicator; and Fig. 6 is a vertical sectional view taken on the plane indicated by the line *a a* of Fig. 1.

Referring to the drawings by numeral, 1 denotes my improved street or station indicating device, which is adapted to be mounted at one end or at any other suitable point in a street-car, railway-car, and the like and which is automatically operated as the car or train approaches streets, crossings, or stations.

The device 1 comprises a suitable casing 2, which is here shown as of rectangular form and provided in its front face or side with a slot or opening 3, across which is adapted to pass an apron 4, bearing the names of the streets, crossings, or stations. This apron 4 passes over two driving-rollers 5 6, which are arranged within the front portion of the box 2 above and below the opening 3 and which

have adjacent to their ends annular series of projecting studs or teeth 7, which are adapted to enter apertures 8, formed in the apron adjacent to its edges.

The apron 4 may be made of any suitable material which will coil or roll itself within the cylindrical boxes or casings 9, mounted within the box 2, adjacent to the rollers 5 6 and having longitudinal slots 10, through which the apron passes. The apron is held in contact with the driving-rollers 5 6 by friction-rollers 11, which are provided upon shafts 12, arranged above and below said rollers, as shown.

The apron is moved in one direction, so that the names of the streets or stations successively appear in the opening 3 when the car moves forward by actuating the shaft of one of the rollers, and it is moved in the reverse direction when the car makes a return trip by actuating the shaft of the other roller.

As the apron is moved in either direction, one of its ends will uncoil in one of the casings 9 and the other end of the apron will be coiled in the other casing 9. This operating mechanism for each of the rollers is very similar and is mounted at the opposite ends of the box 2. Each of these driving mechanisms consists in extending one end of each shaft 13 of the rollers 5 6 and loosely mounting upon such extended end a pinion 14. This pinion is secured upon one end of a sleeve 15 and is adapted to be moved into and out of engagement with a longitudinally-extending key 16, provided upon said end of the shaft 13. When said pinion 14 is moved inwardly upon the shaft, so that the key 16 enters the notch or recess 17, formed in the said pinion, the latter will mesh with a driving-gear 18, secured upon a shaft 19, which is mounted in suitable bearings in one end of the box 2 and in a bracket 20, secured thereon, and when said pinion 14 is shifted outwardly to its dotted-line position (shown in Fig. 1) it will be out of mesh with the gear 18 and out of engagement with the key 16, so that the roller upon the shaft on which it is mounted will not be driven.

In order to retain the pinion in the latter position, I provide upon the sleeve 15, which surrounds the outer end of the shaft 13 and carries a finger piece or knob 21, a pivoted latch-lever 22, which is adapted to have its actuating-spring project one of its ends 23 through an opening in the sleeve 15 and into an annular groove 24, formed in the

outer end of the shaft 13, as shown. By grasping the knob 21 and pressing down upon the outer end of the lever 22 its end 23 may be moved out of the groove 24, and the pinion 14 may be slid longitudinally upon the shaft 13 to move said pinion into and out of mesh with the driving-gear 18.

It will be understood that when the pinion upon the shaft of the roller 5 is engaged with its driving-gear the pinion upon the shaft of the roller 6 is disengaged from its driving-gear, so that the apron or belt 4 will be driven positively in one direction or the other. Each of the shafts 19 has secured upon it a ratchet-wheel 25, which is adapted to be engaged by a pawl upon a suitable operating-lever. As shown, the ratchet-wheel 25 on the shaft 19 at the left-hand end of the box is engaged by a spring-actuated pivoted pawl 26, mounted upon a lever 27. The latter is pivoted, as at 28, at one of its ends and has an offset portion 29 to clear said shaft 19. The opposite or free end of said lever carries the armature 30 of an electromagnet 31, which is mounted within the box or casing 2. The lever 27 may be elevated by a spring or in any other suitable manner; but, as shown, I have provided a weight 32, which is attached to one end of a cord or other flexible connection 33, passed over a pulley 34, and connected to the free end of the lever 27. When the electromagnet 31 is energized, its armature will be attracted and the lever 27 will be swung downwardly to cause its pawl 26 to slip over the teeth of the ratchet-wheel 25, and when said magnet is deenergized the weight 32 will elevate the lever and cause the pawl 26 to actuate the ratchet-wheel, the gear-wheel 18, the pinion 14, and hence the shaft of the roller 5, sufficiently to cause the apron to present the name of the next street in front of the opening 3 of the box 2. The ratchet-wheel 25, which is at the right-hand side of the box and which controls the roller 6, is actuated by a similar spring-seated pawl 35, which is mounted upon a lever 37, pivoted at 38 and having an offset portion to clear the shaft 19. Upon the free end of the lever 37 is suspended a weight 39, which is adapted to actuate said shaft in one direction; but it will be understood that a spring or any other suitable means may be substituted therefor. The lever 37 is actuated in the opposite direction by a lever 40, which is pivoted intermediate its ends, as at 41, within the box 2 and has one of its ends engaged with the under side of the free end of the lever 37. The opposite end 42 of the lever 40 carries the armature of an electromagnet 43, which is mounted centrally in the rear portion of the box 2.

It will be seen that when the magnet 43 is energized the lever 40 will be swung to elevate the lever 37, so that its pawl 35 will slip

over the teeth of the ratchet-wheel 25, and that when it is deenergized the weight 39 will lower the lever 37, and thereby cause the roller 6 to be actuated a distance sufficient to bring a new name before the opening 3.

The two electromagnets 31 and 43 are simultaneously energized by the closing of an electric circuit 44, in which they are included. This circuit 44 also includes a circuit-closing device which has one of its members carried by the trolley-pole of the car in which the indicator is mounted and its coacting member upon the trolley-wire 45 in the center of or adjacent to a street crossing or station. The circuit-closing member upon the trolley-pole 46 is in the form of a lever 47, which is mounted upon an insulated pivot 48 and has a weight 49 at its lower end and a beveled portion 50 at its upper end. This beveled portion is adapted to engage a contact member 51, which is secured upon the trolley-wire, as shown in Fig. 5 of the drawings. This contact member is preferably formed by bending and uniting one or more pieces of wire to form spaced parallel contact-bars 52, which have flared outer ends, so that the beveled portion 50 of the contact-lever 47 may readily enter between them. If desired, this contact member or device may be duplicated upon the opposite side of the trolley-pole, as will be readily understood. While this form of circuit-closing device is preferably employed when the indicators are used upon trolley-cars, it will be understood that the magnets 31 and 43 may be actuated in any other suitable manner, either manually or automatically.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention as defined by the appended claims.

Having thus described my invention, what I claim as new, and desire to secure by Letters Patent, is--

1. In a device of the character described, the combination of an indicating-apron having rows of apertures adjacent to its edges, driving-rollers having radially-arranged projections to enter said apertures, friction-rollers for retaining said apron upon said driving-rollers, drive-shafts, gears upon the latter, pinions slidably mounted upon the shafts of said driving-rollers but keyed to rotate therewith and adapted to be moved in and out of mesh with the gears on the drive-shafts, ratchet-wheels upon said drive-shafts, levers, yielding means to move said levers in one direction, spring-pawl carried

by said levers and engaged with said ratchet-wheels, and electromagnets for actuating said levers in the reverse direction.

2. In a device of the character described, the combination of an indicating-apron, a driving-roller therefor, a drive-shaft, a gear upon said drive-shaft, a pinion upon the shaft of said roller mounted to slide thereon and to rotate therewith, a sleeve upon said pinion, a latch-lever upon said sleeve and

adapted to enter a groove in the shaft of said roller, substantially as shown and described.

In testimony whereof I have hereunto set my hand in presence of two subscribing witnesses.

CHARLES A. MYERS.
